UNITED STATES PATENT OFFICE.

CHARLES B. BROOKHART, OF CLEVELAND HEIGHTS, OHIO.

HOLDER FOR CLOTHESLINES AND THE LIKE.

1,408,261.

Specification of Letters Patent. Patented Feb. 28, 1922.

Application filed September 25, 1920. Serial No. 412,758.

To all whom it may concern:

Be it known that I, CHARLES B. BROOKHART, a citizen of the United States, and a resident of Cleveland Heights, county of Cuyahoga, and State of Ohio, have invented 5 a new and useful Improvement in Holders for Clotheslines and the like, of which the following is a specification, the principle of the invention being herein explained and 10 the best mode in which I have contemplated applying that principle, so as to distinguish it from other inventions.

The present improvements, relating, as indicated, to clothes-line holders, have regard 15 more particularly to holders on the order of a reel or spool whereon a clothes-line or other cable or wire may be conveniently wound, and in turn unwound therefrom. One object of the invention is to provide a 20 device of this sort which may be readily carried about and operated with one hand. At the same time the device provides a self-contained holder for the line, whatever the character or use of the latter, so that such 25 line can be stowed away without danger of becoming tangled up or snarled.

To the accomplishment of the foregoing and related ends, said invention, then, consists of the means hereinafter fully described 30 and particularly pointed out in the claims, the annexed drawing and the following description setting forth in detail certain mechanism embodying the invention, such disclosed means constituting, however, but 35 one of various mechanical forms in which the principle of the invention may be used.

In said annexed drawing:

Fig. 1 is a perspective view of my improved holder; Fig. 2 is a central axial section thereof on plane 2—2, Fig. 3, showing 40 a line partly wound thereon; and Figs. 3 and 4 are transverse sections of such holder taken on planes indicated by lines 3—3 and 4—4, respectively of Fig. 2.

As clearly shown in the aforesaid drawing, my improved holder consists, in effect, 45 of a hollow or tubular spool, the body 1 of which is preferably, although not necessarily, of frusto-conical form. The ends of such 50 body are provided with flanges 2 and 3 of corresponding diameters, i. e. the flange 2 on the smaller end of the body is of less diameter than the flange 3 at the larger end. Transversely secured within the body 1 is 55 a handle 4 adapted to be conveniently and firmly grasped by one hand of the user, such

hand being inserted from the larger end of the holder, and such handle being preferably located somewhat more closely adjacent such end than the opposite smaller end, (see 60 Fig. 2.)

The handle 4 may be conveniently made of wood turned to the form shown, or of sheet metal, while the body and flanges of the holder are preferably fashioned of sheet 65 metal so that the holder in its entirety is light and easy to manipulate.

The clothes-line, cable, wire or the like is of course wound about the body 1 between flanges 2 and 3 in familiar fashion, the inner end 5 of such line being knotted and held in a V-shaped notch 6 formed in the body adjacent the flange 2. After the line has been wound up on the holder, either 70 completely or partially, its outer or freed end 7 is secured by being passed through a notch 8 in the periphery of the flange 3, and then passing such end under a spring clip 9 that is preferably stamped up directly out of the metal composing such flange, (see 75 Fig. 2).

In use, assuming the line to be thus wound up on this spool, the outer end 7 thereof is freed from the holding means provided on the flange 3 and secured to a clothes-line 80 hook, pole or other fixed point of attachment, then by simply taking hold of the handle 4, (preferably with the left hand) the user can unwind the line, or any desired portion thereof, from the spool, such line 85 running freely over the flange 2 at the smaller end of such spool. Should it not be desired to use all the line, the latter is then secured at an intermediate point to flange 3 90 as before. Conversely, when it is desired to 95 re-wind the line on to the holder it is freed from flange 3 and wound up by holding the handle 4 as previously, with the left hand, and winding the line on to the body 1 with the right hand. The device, it will be seen, 100 is extremely simple, compact and inexpensive to manufacture, and yet provides numerous advantages over the more complicated reels and the like which have heretofore been proposed as a solution of the problem of 105 retaining clothes-lines and other lines, that require to be frequently wound and unwound, from becoming tangled up and snarled.

Other modes of applying the principle of 110 my invention may be employed instead of the one explained, change being made as

regards the mechanism herein disclosed, provided the means stated by any of the following claims or the equivalent of such stated means be employed.

5 I therefore particularly point out and distinctly claim as my invention:—

1. In a device of the character described, the combination with a hollow flanged spool, adapted to have a line or the like wound 10 thereabout, of a handle attached to said spool transversely of the axis and adjacent one end thereof, for bracing the same and permitting free manipulation thereof.

2. In a device of the character described, 15 the combination with a hollow flanged spool, adapted to have a line or the like wound thereabout, of a handle attached to said spool transversely of the axis and adjacent one end thereof, for bracing the same and permitting free manipulation thereof, and 20 means adjacent the respective ends of said spool adapted to engage and retain such line.

3. In a device of the character described, 25 the combination with a hollow flanged spool, adapted to have a line or the like wound

thereabout, of a handle attached to said spool transversely of the axis and adjacent one end thereof, for bracing the same and permitting free manipulation thereof, means adjacent one end of said spool adapted to 30 engage and retain an end of such line, and means adjacent the other end of said spool adapted to engage and retain such line at an intermediate point.

4. In a device of the character described, 35 the combination with a hollow spool of frusto-conical form, flanged at each end and adapted to have a line wound thereabout between such flanges, of a handle secured within said spool transversely of the axis thereof, 40 said spool being formed adjacent its smaller end with a notch adapted to engage and retain a knotted end of said line, and means on the flange at the larger end of said spool adapted to engage and retain the line at an 45 intermediate point.

Signed by me, this 22nd day of September, 1920.

CHARLES B. BROOKHART.
